RAIL FLANGE LUBRICATOR

Charles Stern, Jersey City, N. J., assignor to
Ardco Manufacturing Company, Hoboken, N. J.,
a corporation of Delaware

Application February 19, 1934, Serial No. 712,067

14 Claims. (Cl. 184—3)

The present invention relates to lubricators, and more particularly to a lubricator of the type which is adapted to be mounted against a rail for supplying lubricant along one side of the head 5 of the rail, so that the lubricant may be picked up by wheel flanges and distributed for a considerable distance along the side of the rail from the lubricator.

An object of the present invention is to provide 10 a lubricator of this character which is of very simple construction and admits of simple installation, and wherein the lubricant is fed directly from a manifold or chamber in the device through a plurality of suitably spaced apart nozzles carried thereby into the desired spaced apart positions along the side of the rail head, and to provide a protecting plate so supported as to prevent damages to the nozzles by the flanges of the wheels passing over the rail.

Another object of the present invention is to provide the lubricator with tubes or nozzles which are individually and replaceably mounted upon the bracket or body part of the lubricator so that at slight cost the nozzles may be replaced 25 when worn or damaged.

The invention also aims at the provision of a lubricator construction of this character in the use of which the maintenance cost is at a minimum and to displace structures of this character 30 wherein the tubes or nozzles are integral with the manifold or supply chamber and wherein various other structural features are resorted to making the nozzles or feeding portions of the device integral therewith.

A still further object of the invention is to provide a construction of lubricator wherein the parts are so mounted that the lubricator may be adjusted to rails of different types and different 35 conditions incident to wear, and wherein the bracket or body part is supported mainly from the rail flange to take up pressure of wheel flanges and the like and to thus reduce to a minimum shearing forces exerted upon bolts or other devices utilized in holding the bracket or body portion to the web of the rail.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of a rail lubricator constructed according to the present invention and as applied to one side of the rail.

Figure 2 is a like view but with the protecting plate removed and the lower portion of the bracket or manifold shown in section.

Figure 3 is a transverse section taken through one end of the lubricator substantially on the line 5—3 of Figure 1.

Figure 4 is a like view taken through the intermediate portion of the lubricator substantially on the line 4—4 of Figure 1.

Figure 5 is another transverse sectional view taken through the lubricator near one end thereof substantially on the line 5—5 of Figure 1.

Figure 6 is a detail perspective view of the bracket or manifold with the various nozzles, protecting plate and supports removed therefrom.

Figure 7 is a detail inner face perspective view of the protector plate, and

Figure 8 is a detail perspective view of one of the feeding nozzles employed.

Referring now to the drawings, 10 designates 20 the base of a rail of conventional construction having a web 11 and a head 12.

The body portion of the lubricator comprises a bracket or manifold 13 which, as best shown in Figure 5, may be of regular cross section providing a lubricant receiving and retaining chamber 14 and which at its inner side is flat for face engagement against one side of the web 11 of the rail, the bracket or manifold having a plate portion 15 which extends upwardly from the chamber 14, is of less width than the chamber, and is offset inwardly with its inner face in the plane of the inner face of the manifold or chamber 14. The bracket thus constructed is provided at opposite ends with flat lugs 16 forming extensions 35 of the inner wall portion of the bracket adapted to lie against the web 11 and which are provided with vertically elongated slots 17 for the reception of bolts 18 therethrough to clamp the bracket against the web 11. The bolts 18 may be introduced through the web 11 at the outer side thereof and extend through the slots 17 and through pressure equalizing washers 19, shown in Figures 1 and 3. The washers 19 have bolt receiving openings therethrough snugly fitting the 45 bolts 18 and are of relatively large surface area so as to overlie a considerable portion of the outer surface of the adjacent lug 16. Each bolt 18 carries a nut 20 turned up against the adjacent washer 19 so that the pressure of the nut 20 is 50 distributed through the washer 19 over considerable surface area of the lug 16.

This insures a firm hold on the bracket and prevents injury to the marginal edge portions of the slots 17 and to the bolt 18 and its nut 20.

The bracket or body portion is supported directly from the base 10 of the rail. To accomplish this the manifold 13 is provided at suitable spaced points along its front wall with outwardly and downwardly inclined ears 21 which are of considerable thickness and provided each with an internally threaded opening for receiving a threaded bolt 22, the heads of the bolts 22 being disposed lowermost for direct contact with the base 10 of the rail.

In positioning and adjusting the manifold or body portion of the lubricator, the bracket or manifold 13 is placed against the web 11 in the desired vertical position of adjustment and the bolts 18 are then tightened to hold the bracket flat against the web 11. The supporting bolts 22 are now turned downwardly through their ears 21 until the heads of the bolts 22 take purchase against the adjacent portion of the rail base 10, the bolts 22 being turned down until they effect a firm engagement or contact with the rail base so as to take up strain or pressure transmitted through the manifold or bracket from the wheel flanges. This relieves the bolts 18, to a considerable extent, against undue strain or shearing action.

The upper wall of the chamber 14 is provided with a suitable number of threaded openings 23 which are disposed adjacent the inner wall of the chamber 14 and communicates therewith. To accommodate the openings 23 and leave the space therebetween free, the back plate 15 is provided in its front side with a plurality of depressions or cut-outs 24 forming recesses which register with the openings 23, and which are preferably of a slightly greater diameter than that of the openings. It will be noted, from Figure 6 particularly, that the openings 23 are offset to a considerable extent within the recesses 24, and that the front face of the plate 15 is relatively flat between the recesses 24 for supporting a protector plate 25, shown in detail in Figure 7. The manifold 13 is provided with an inlet 26 comprising a threaded flange at the outer side of the manifold and intermediate its ends. The flange 26 is adapted to receive the adjacent end of a feed pipe or the like for introducing lubricant under pressure to the chamber 14. To facilitate manufacture of the device and also cleaning out of the chamber 14, the bracket or manifold is provided in opposite ends with removable plugs 27 which may be threaded or otherwise suitably secured in the ends of the manifold.

The manifold 13 carries a plurality of nozzles 28. In Figure 8 one of the nozzles is shown and the same comprises a base plug 29 externally threaded to engage in the threaded openings 23 of the manifold and each plug 29 has a kerf 30 for receiving the bit of a screw driver or the like to facilitate the positioning and removal of the plug 29 relative to the opening 23.

In Figure 4 a bottom plug 31 is shown in line with the adjacent opening 23, and there is a similar plug 31 provided for each opening 23. The bottom plugs 31 are of sufficient size to admit of the quick and easy positioning and removal of the nozzles 28 through the bottom of the manifold as the nozzles are moved into place or withdrawn therefrom.

Each nozzle 28 is in the form of a tube or pipe which is flattened at its outer end with the flat side outermost, as shown in Figure 4, so as to provide a slotted outlet 32 extending in the general direction of the length of the lubricator or rail. The slotted outlet 32 is beveled so as to

recede outwardly from the adjacent head of the rail, as shown in Figure 4, so that the lubricant will be distributed against the side of the rail head in the form of an elongated mass. A tube 28 is mounted in each recess 24 of the manifold 5 and the protector plate 25 seats at its inner side in face engagement with the outer side of the back plate 15.

The protector plate 25 has on its inner side grooves or recesses 33 in register with the depressions 24 for accommodating the nozzles or tubes 28 without crushing the same and to protect the nozzles. At the upper edge, the protector plate 25 is provided with a notch 34 for each outlet end 32 of the nozzles and the outer face 15 of the protector plate 25 at its upper edge is beveled at 35 to accommodate the wheel flanges and to protect the nozzles or tubes 28 at their upper ends so that the upper ends may extend well up into the light between the rail head 12 and the 20 wheel flange.

The protector plate 25 is provided at suitable points throughout its length with openings 36 therethrough for the reception of machine screws or the like and the back plate 15 is provided with 25 corresponding threaded openings 37 for receiving the threaded ends of the machine screws 38, shown in Figure 5, so that the protector plate 25 may be clamped securely in flat engagement against the back plate 15.

It will be noted that the flattened upper ends of the tubes or nozzles 28 are of less dimensions than that of the plug or bushing 29 so that the nozzles may be readily introduced through the bottom of the chamber 14 and upwardly through 35 the openings 23. It will also be observed that the milled out grooves 33 in the inner face of the protector plate 25 and the depressions 24 are of sufficient size to accommodate the tubes or nozzles without exerting pressure upon or crushing 40 them while at the same time permitting the protector plate 25 to lie flat against the outer face of the back plate 15.

The outer structure or casing thus provided for the nozzles or tubes 28 is relatively strong and 45 interbraced so that the protector plate 25 cannot be buckled or distorted under pressure from the wheel flanges.

It is obvious that various changes and modifications may be made in the details of construction and design of the above specifically described embodiment of this invention without departing from the spirit thereof, such changes and modifications being restricted only by the scope of the following claims.

What is claimed is:—

1. A rail flange lubricator comprising a bracket having a chambered lower portion, means for clamping the bracket against one side of the web of a rail, supporting means adjustably mounted 60 on the outer lower portion of the bracket for direct engagement with the base of the rail to support the bracket, a plurality of independent nozzles mounted upon the bracket in communication with said chamber, and a protector plate 65 independent of the rail mounted on the bracket across the outer sides of the nozzles, said nozzles and protector plate extending above the bracket and adapted to lie against the side of the head of a rail.

2. A rail flange lubricator, comprising a bracket having a flat inner face for engagement against the side of a rail web and having an enlarged chambered lower end, a plurality of nozzles carried by the bracket at the top of said chamber 75

- and adapted to engage against the side of the rail head, a protector plate independent of the rail mounted on the bracket and engaging across the outer sides of the nozzles, and adjustable supporting means carried upon the bracket for direct engagement with the base of the rail and disposed outwardly of said chambered portion of the bracket to support the same against thrust of wheel flanges and the like.
3. A rail flange lubricator, comprising a body bracket, means for securing the bracket against one side of a rail web, said bracket having an upper back plate portion and a lower chambered portion extending beyond the plate portion, a plurality of nozzles mounted on the chambered portion, said plate portion having recesses in its outer side to accommodate said nozzles, a protector plate secured against the outer side of the back plate and having grooves in its inner side registering with the nozzles to protect the latter, said nozzles and protector plate adapted to engage against the inner side of a rail head and being beveled to accommodate wheel flanges, and supporting means carried upon the lower outer portion of the body bracket for direct engagement with the base of the rail at a point remote from the web thereof.
4. A rail flange lubricator, comprising a body bracket having a lower chambered portion and an upstanding back plate, said body bracket having lugs at opposite ends co-extensive therewith, bolts engaging through said lugs and adapted to engage the rail web, said lugs having vertical slots therein for the reception of the bolts to permit vertical adjustment of the body bracket, nuts carried upon said bolts, pressure distributing plates carried by the bolts beneath said nuts and extending over a substantial area of the adjacent lug of the body bracket, a plurality of independent removable nozzles carried on the chambered portion of the body bracket, a protecting plate mounted on the body bracket and extending across the outer sides of the nozzles, and adjustable set screws carried by the lower outer portion of the bracket plate for engagement with the base of a rail to directly support the bracket plate against pressure of wheel flanges.
5. A rail flange lubricator, comprising a body bracket having a back plate for engaging the web of a rail and having a chambered portion at its lower end outstanding from the plate, threaded ears carried by said chambered portion and overhanging the base of a rail, set screws threaded in said ears for binding engagement with said rail base to directly support the body bracket, clamping means engaging the body bracket and adapted to engage the rail web for holding the bracket against the latter, a plurality of independently mounted nozzles spaced along the upper side of the chambered portion of the body bracket in front of the back plate thereof, said nozzles extending upwardly from the body bracket and adapted to lie against the inner side of a rail head, and a protector plate secured flat against the bracket plate across the outer sides of said nozzles and having a beveled upper end for protecting the nozzles, said bracket plate and protector plate having registering recesses in their abutting faces receiving the nozzles to protect the same.
6. A rail flange lubricator, comprising a body bracket having a lower manifold portion and an upper back plate at the inner side of the manifold, means for clamping the body bracket against a rail web, said bracket body having a plurality of spaced threaded openings in the upper wall of the manifold portion thereof and having registering openings in the bottom wall of said manifold portion, nozzles proportioned for introduction through the registering openings in the walls of the manifold portion and having base plugs for threaded engagement in the top openings of the manifold portion to support the nozzles in upwardly projecting position for engagement against the side of a rail, removable plugs mounted in the lower openings of the manifold portion, and a protector plate independently of the rail carried by the body bracket across the outer sides of said nozzles to protect the same.
7. A rail flange lubricator, comprising a manifold having upper and lower walls with registering openings therein, nozzles removably mounted in the upper openings of the manifold and adapted for removal downwardly through the lower openings of the manifold, closure plugs for the lower openings of the manifold, a back plate rising from the inner side of the manifold and having recesses in its outer face to accommodate the nozzles, a protector plate secured across the outer sides of the nozzles and against the back plate and having grooves therein accommodating the nozzles, means for securing the manifold and back plate at the desired height against a rail web, and adjustable supporting means mounted on the outer side of the manifold for engagement with the base of a rail to support the manifold and back plate against pressure of wheel flanges against the protector plate.
8. A rail flange lubricator, comprising a manifold having upper and lower registering openings and opposite end openings, nozzles having threaded plugs on their lower ends removably engaging in the upper openings of the manifold and adapted for removal downwardly through the lower openings for ready replacement of the nozzles, plugs closing the lower openings, plugs closing the end openings, a back plate carried by the manifold having lug extensions at opposite ends, said lugs having vertical slots therein, clamping bolts adapted for engagement through the web of a rail and engaging through said slots and having nuts on their outer ends, pressure distributing plates mounted on the bolts and engaging over the outer faces of said lugs to distribute pressure of said bolts thereover, said back plate having recesses therein registering with the inner sides of the top openings in the manifold to provide spaces for said nozzles, a protector plate secured across the outer face of the back plate and having recesses therein registering with the nozzles to maintain the protector plate out of binding engagement therewith, said protector plate and nozzles adapted to engage against the inner side of a rail head and the protector plate having notches in its upper end for the reception of the upper ends of said nozzles.
9. A rail lubricator comprising a bracket having an integral chambered lower portion, means for clamping the bracket against one side of the web of a rail, a plurality of independent nozzles mounted on the chambered portion and being in communication therewith, and a protector plate mounted on a bracket across the outer sides of said nozzles, said nozzles and protector plate extending above the bracket and adapted to lie against the side of the head of the rail.
10. A rail lubricator comprising a member having a vertical wall, adapted to contact the web of the rail, a pair of parallel upper and lower horizontal walls extending from said vertical wall,

- a vertical wall interconnecting said horizontal walls and forming a conduit with said first vertical wall, end walls at the opposite ends of said conduit, said first vertical wall extending beyond the opposite ends of said conduit and being formed with vertical slots for receiving attaching devices for attaching said member to the web of said rail, a plurality of lugs extending from said second vertical wall, and set screws screwed to said lugs and adapted to contact the base of the rail for adjusting the vertical height of said member.
11. A rail lubricator comprising a member having a vertical wall adapted to contact the web of the rail, a pair of parallel upper and lower horizontal walls extending from said vertical wall, a vertical wall interconnecting said horizontal walls and forming a conduit with said first vertical wall, end walls at the opposite ends of said conduit, said first vertical wall extending beyond the opposite ends of said conduit and being formed with vertical slots for receiving attaching devices for attaching said member to the web of said rail, a plurality of lugs extending from said second vertical wall, set screws screwed to said lugs and adapted to contact the base of the rail for adjusting the vertical height of said member, the ends of said conduit having screw threaded openings, and screw threaded plugs screwed to said openings for closing the ends of said conduit.
12. A rail lubricator comprising a member having a vertical wall adapted to contact the web of the rail, a pair of parallel upper and lower horizontal walls extending from said vertical wall, a vertical wall interconnecting said horizontal walls and forming a conduit with said first vertical wall, end walls at the opposite ends of said conduit, said first vertical wall extending beyond the opposite ends of said conduit and being formed with vertical slots for receiving attaching devices for attaching said member to the web of said rail, a plurality of lugs extending from said second vertical wall, set screws screwed to said lugs and adapted to contact the base of the rail for adjusting the vertical height of said member, the ends of said conduit having screw threaded openings and screw threaded plugs screwed to said openings for closing the ends of said conduit, said second vertical wall having an inlet opening in an intermediate portion thereof for receiving an inlet pipe whereby grease may be supplied to said conduit.
13. A rail lubricator comprising a member having a vertical wall adapted to contact the web of the rail, a pair of parallel upper and lower horizontal walls extending from said vertical wall, a vertical wall interconnecting said horizontal walls

and forming a conduit with said first vertical wall, end walls at the opposite ends of said conduit, said first vertical wall extending beyond the opposite ends of said conduit and being formed with vertical slots for receiving attaching devices for attaching said member to the web of said rail, a plurality of lugs extending from said second vertical wall, set screws screwed to said lugs and adapted to contact the base of the rail for adjusting the vertical height of said member, the ends of said conduit having screw threaded openings and screw threaded plugs screwed to said openings for closing the ends of said conduit, said second vertical wall having an inlet opening in an intermediate portion thereof for receiving an inlet pipe whereby grease may be supplied to said conduit, said upper horizontal wall being formed with a plurality of vertical, spaced, screw threaded through openings, members screwed to said screw threaded openings and having through openings therein, and nozzles secured to said last mentioned members and having mouths at the upper ends thereof adjacent the head of the rail.

14. A rail lubricator comprising a member having a vertical wall adapted to contact the web of the rail, a pair of parallel upper and lower horizontal walls extending from said vertical wall, a vertical wall interconnecting said horizontal walls and forming a conduit with said first vertical wall, end walls at the opposite ends of said conduit, said first vertical wall extending beyond the opposite ends of said conduit and being formed with vertical slots for receiving attaching devices for attaching said member to the web of said rail, a plurality of lugs extending from said second vertical wall, set screws screwed to said lugs and adapted to contact the base of the rail for adjusting the vertical height of said member, the ends of said conduit having screw threaded openings and screw threaded plugs screwed to said openings for closing the ends of said conduit, said second vertical wall having an inlet opening in an intermediate portion thereof for receiving an inlet pipe whereby grease may be supplied to said conduit, said upper horizontal wall being formed with a plurality of vertical spaced screw threaded through openings, members screwed to said screw threaded openings and having through openings therein, nozzles secured to said last mentioned members and having mouths at the upper ends thereof adjacent the head of the rail, and a protector plate attached to said first member and adapted to cover said nozzles, the inner surfaces of said first member and protector plate having registering recesses for receiving said nozzles.

CHARLES STERN.
